DESIGN FOR A TYPEWRITING MACHINE

James H. Rand, Jr., Stamford, and Russell G. Thompson, West Hartford, Conn., assignors to Remington Rand Inc., Buffalo, N. Y., a corporation of Delaware

Application November 30, 1938, Serial No. 81,490

Term of patent 7 years

To all whom it may concern:

Be it known that we, James H. Rand, Jr., and Russell G. Thompson, citizens of the United States residing respectively at Stamford, in the county of Fairfield and State of Connecticut, and West Hartford, in the county of Hartford and State of Connecticut, have jointly invented a new, original, and ornamental Design for Typewriting Machines, of which the following is a specification, reference being had to the accompanying drawings, forming a part thereof.

Fig. 1 is a side elevation of a typewriting machine showing our design.

Fig. 2 is a front elevation of the same.

Fig. 3 is a rear elevation of such machine, and Fig. 4 is a top plan view thereof.

We claim:

The ornamental design for a typewriting machine, as shown.

JAMES H. RAND, JR.
RUSSELL G. THOMPSON.
